UNITED STATES PATENT OFFICE

153,400

DESIGN FOR A BRACELET OR SIMILAR ARTICLE

Irving Stein, Brooklyn, N. Y.

Application October 15, 1948, Serial No. 149,131

Term of patent 7 years

(Cl. D45—4)

To all whom it may concern:

Be it known that I, Irving Stein, a citizen of the United States of America, residing in Brooklyn, county of Kings, and State of New York, have invented a new, original, and ornamental Design for a Bracelet or Similar Article, of which the following is a specification, reference being had to the accompanying drawing, forming part thereof.

Fig. 1 is a plan view of a bracelet or similar article, showing my new design.

Fig. 2 is an edge view thereof.

The dominant feature of my design resides in the links shown in full lines, which links are repeated alternately throughout the length of the bracelet as indicated by the broken line disclosure.

My design for a bracelet is characterized by the octagonal shaped links, which links have a substantially large, round center opening, arranged alternately with narrow, solid rectangular links, said solid links being substantially the

same in length as, but slightly greater in proportionate depth than, the octagonal shaped links.

I claim:

The ornamental design for a bracelet or similar article, substantially as shown and described.

IRVING STEIN.
